Specification for Design.

Patented Sept. 25, 1917.

Application filed June 20, 1917. Serial No. 175,825. Term of patent 14 years.

To all whom it may concern:

Be it known that I, ELLWOOD C. JOHNS, a citizen of the United States of America, residing at No. 211 Myrtle avenue, Jersey City, in the county of Hudson and State of New Jersey, have invented a new, original, and ornamental Design for a Casing for Thermostats, of which the following is a specification, reference being had to the accompanying drawing, wherein—

Figure 1 is a front elevation;

Fig. 2 is a side elevation, the general de-

sign being drawn only at the top and bottom thereof, and the part omitted corresponding to that shown.

I claim:—

The ornamental design for a casing for thermostats, as shown.

In witness whereof, I have hereunto signed my name.

ELLWOOD C. JOHNS.
